BOTTLE DISPENSING DEVICE

Anthony Kuhn and Charles H. Heitman, New York, N. Y.; said Heitman assignor to Andrew D. Reid, Weehawken, N. J.

Application August 31, 1932, Serial No. 631,129

5 Claims. (Cl. 312—36)

Our present invention relates to an improvement in dispensing devices, and, more especially to a cooling means, such as a refrigerator arranged to dispense bottled, cold beverages from a series of cooled, fixed storage-magazines to a common point of removal from the refrigerator.

In general, the present device, in its main principles of filling and discharging bottles or similar cylindrical articles is similar to our co-pending U. S. application Serial #470,826, filed July 26th, 1930, for Vending devices.

The bottle holding means of the present device are similar to those disclosed in the above noted application, with the exception that, in the present instance means have been provided to create greater rolling friction to the falling bottles or bodies and to silence the gravitational feed action thereof as will be later pointed out in detail.

A further advantage in the present improvement relates to the provision of means for cushioning and for also silencing the final drop of the article to the common dispensing point, such cushioning means being so arranged as to cause the bottles or articles so selected, from plural selection points, to be automatically rolled to said dispensing or removal point.

The foregoing, and many other novel features will be ascertained as the herein description proceeds, and it is obvious that modifications may be made in the herein outlined improvements, without departing from the spirit hereof or the scope of the appended claims.

In the drawings,

Fig. 1 is a front elevational view of one form of a refrigerator embodying our invention showing a portion of the front broken away to show the structure of one of the bottle receiving and feeding channels;

Fig. 2 is a plan view of Fig. 1;

Fig. 3 is a sectional view taken on the line 3—3, Fig. 1, looking in the direction of the arrows;

Fig. 4 is an enlarged fragmental section of the lower portion of the refrigerator and the dispensing device with a part of the front broken away to show the cushioning and dispensing means;

Fig. 5 is a fragmentary sectional view taken on the line 5—5, Fig. 4, looking in the direction of the arrows;

Fig. 6 is a fragmentary enlarged view showing some of the details of construction at the lower end of the channel in which the rear

mounting of the rotary bottle discharger is disclosed;

Fig. 7 is an enlarged fragmentary view in cross section showing details enlarged of the bottle rotating baffles and the friction and silencing means associated therewith.

In Fig. 1 the entire refrigerator is indicated by 1, and while not fully shown, the refrigerator is constructed to be operated by any standard electrical refrigerator unit, the motor being sealed within the lower half of said refrigerator and being freely open to atmosphere by the louvres 2. The cold unit and the piping thereof is not shown, it being well understood to those skilled in the art, and the refrigerating means utilized are not claimed herein, and being well known, need not be further described.

The top portion of the refrigerator 1 above the louvre section 2, as shown in Figs. 1, 3 and 4, comprises a series of inbuilt channel members formed of upright side strips 3 and end strips 4, so that each associate bottle receiving channel is substantially rectangular from top to bottom.

As constructed, these channel forming members as made of spaced metal strips 3 and 4, are open to the cooling action of the circulating cold air so that at the front and rear spaces as at 5 and 5', Fig. 3, there is a vertical channel and there are also spaces between the strips 3—3, such as at 6, Fig. 3, to permit cold air to circulate through the bottle receiving channels so that the bottles held therein are thoroughly cooled.

In Fig. 1 there is shown a partially fragmented channel member showing the bottles 7 piled therein, looking from the front of the device, said bottles being held in a staggered relation within said channels by staggered baffles generally denoted by 8, said baffles being comprised of an outstanding lower bracket portion 9, Fig. 7, the bent flange 10 of which is welded or otherwise affixed to the side wall strips 3, the outer end of said flange support 9 being slightly downwardly bent and having the overfolded end 11 of an angular baffle member 12 connected therewith, said member 12 being of metal and having its upper flanged end 13 affixed to the metal side wall strip 3.

Above the flange 13 there is a clip strip 14 welded at its end 15 also to the side wall 3 and underneath the lower open end 16 of which there is introduced a web of sheet rubber 17, Fig. 7, the clip 14 being bent down upon the upper end of said web to firmly hold the same in operative position, the lower end 18 of said web 17 being loose and resting upon the lower end of the inclined

baffle 12 so that the said web is loosely held in operative position, as in Fig. 7.

It is to be understood that each of the baffles shown in the vertical channels of the herein construction are each provided with metallic-rubber baffle construction above disclosed.

The foregoing construction therefore disposes the flexible rubber web 17, in a loose and cushion-like suspension upon the baffle plate 12, said webs, 10 upon the reception of each bottle, as they pass downwardly towards the point of dispensing, being compressively acted upon to receive the blows of the bottles as they fall and at the same time to exert a friction on the sides of the bottles to 15 cause the bottles to rotate in the direction of the arrow A, Fig. 7, as the bottles roll downwardly from baffle to baffle.

As in the previously noted pending application Serial No. 470,826, the present baffle construction 20 is of such a nature as to cause the bottles as they fall to be rotated first in one direction upon contacting with and leaving a baffle and then to rotate in the opposite direction upon contacting with and leaving the next successive baffle, and therefore 25 be retarded in its gravity actuated downward feeding, and this action is such that should the channels be entirely empty, a bottle introduced at the top thereof will fall to the bottom with a series of oppositely rotated movements from baffle to baffle, thereby being greatly retarded in its fall, and absolutely without breakage. If another bottle is introduced from the top in the same manner, it will fall to the bottom and rest against the first introduced bottle at the bottom without 30 breakage.

In order to fill the channels any desired form of top opening may be utilized. In the present instance, as in Figs. 1 and 2, the top of the refrigerator is shown as being provided with a series 40 of hinged doors 19, each of the said doors being hinged at the rear by hinges 20 to the rear wall 21 of the refrigerator, and each of the said doors being provided with lifting knobs 22 whereby the said knobs may be operated to lift the doors to 45 open each channel so that bottles may be introduced, as desired, for filling said channels, after which the doors are closed.

It is desired in the present device to carry a plurality of different types of beverages in each 50 channel and to that end the front face of the refrigerator 1 is provided with a series of name plates B, these being small metal frames into which may be introduced tags with the name of the beverage, which is included in its associate 55 channel. At the bottom of each channel as in Figs. 3, 4, 5 and 6, there is provided a manually rotatable half cylinder 23 which may be made of an outer cylindrical metal shell 23, Fig. 6, and lined on its inner side with a cemented on 60 rubber pad 24 upon which is overlaid, as in Fig. 4, and cemented thereto a thick sponge rubber pad 25, so that when the cylindrical, rotatable bottle receiving and dispensing tray is in normal 65 bottle receiving position, as in the first left hand channel in Fig. 4, the tray is in the upwardly open position to receive a bottle falling from the said channel above, from the lowermost baffle therein. The falling bottle will land on the soft sponge rubber pad 25, and the force of the fall 70 will be broken and the fall of the bottle be silenced.

As shown in Fig. 4, and in Figs. 5 and 6 the cylindrical bottle receiving tray has two round disk like ends 26 and 27 and an intermediately 75 located bottle end stopping disc 27', to which

the outer metal shell 23 is attached. On the rear of the disk 27 there is a short trunnion or shaft 28 projecting from the center thereof.

The rear channel forming wall strip 4, Fig. 6, has a circle cut-out 29, sufficiently large to permit the bottle receiving shell 23 to rotate freely 5 therein and in order to support the trunnion 28 for rotation, there is provided at said rear end a vertical strap bracket 30 which is riveted by rivets 31 to the wall strip 4, the said strap 30 10 being offset as in Fig. 3, so as to be connected to the said rear wall 4, and its lower offset extension 4'.

A similar bracket 32, Fig. 5, is affixed to the other front wall forming strip 4, Fig. 5, and a 15 shaft 33 is also centrally affixed to the fixed disk 26, said shaft 33 extending through the front wall portion of the refrigerator as in Fig. 5, and having a turning handle 34 attached thereto, these 20 handles being fully shown in Fig. 1 and also in Fig. 2. The wall of the refrigerator, all around, as in Figs. 3 and 5, is made of an inner and outer shell made without joints and the space between the said inner and outer shells as in Figs. 5 and 3 is filled with an insulation or cork filling C.

The rotating handles 34, as in Fig. 1, are utilized to rotate the bottle receiving cylinders 23 from the bottle receiving position to the bottle discharging position, downward, when it is desired to extract a bottle from any desired 30 channel member. As in Fig. 4, the second bottle receiving cylinder 23 has been rotated to discharge a bottle D, shown in dotted lines, and at the same time to hold up the next bottle until the cylinder 23 has been restored to the non bottle discharging position, and the restoration of the receiving cylinder 23 to bottle receiving position is caused by means of a spring 35, fully 35 shown in Fig. 6, the said spring being attached by a pin 36 to the end wall 4, and the other end 40 of the spring being attached to a pin 37 which is attached to the rear end disk 27, so that when a handle 34 has been rotated to discharge a bottle and is released, the spring causes the bottle receiving sleeve to rotate back to bottle 45 receiving position.

As will be noted from the fragmented portion of Fig. 4, there are a plurality of adjacent bottle receiving channels in which the bottles are indicated in dotted lines in their operative positions resting against the staggered baffles in each bottle receiving channel, and it will be noted that each of the said bottle receiving channels are provided with a separate rotatable bottle receiving and discharge means 23, all actuated as previously described.

It will further be noted that there is mounted, below the open ends of said channels and which are controlled by the said bottle receiving and discharging means 23, a bent metal plate 38, said 50 plate being angularly inclined in two directions from a peak 39 and being supported by a side flange 40 which is suitably attached to opposite sides of the inner refrigerator walls. This double inclined plate 38 has fixedly mounted thereon a 55 heavy sponge rubber pad or blanket 41, which is cemented to said plate 38 in such a manner as to also be angularly inclined in both directions, to the right and to the left, Fig. 4, so that when a bottle is dropped from any of the three or four 60 intermediate channels, except both extreme right and left hand end channels, the bottles so discharged fall upon the sponge rubber pad 41 as shown by bottle D, dotted, and will then roll to a 65 position shown by the dotted bottle E.

When the bottle is discharged from position D to position E, it falls upon a second rubber blanket 42 which is also inclined with a double angle from its outer ends to the center, being depressed 5 at 43, but being higher on both its ends and thereafter rolls in the direction of the arrow F to the dotted bottle position G, Fig. 4, where it is in a central position before the dispensing or discharge door 44. Thereafter, the door 44 may be opened 10 and the bottle extracted therefrom, and the door then closed.

In the case of the extreme right hand and left hand bottle holding channels, these operate somewhat differently than above described. For instance when the receiving and discharging sleeve 15 23 on the left hand side, Fig. 4, is rotated, the bottle falls from the discharging position directly to the sponge rubber pad 42 at position E, and thereafter rolls to position G as previously described, and the action of discharge from the extreme right hand bottle receiving channel is the same, this extreme right hand bottle receiving channel however, not being shown.

Thus it will be noted that we have provided a 25 bottle discharge mechanism at the bottom of each bottle carrying channel member wherein bottles may be discharged one by one from any one of the adjacent vertical rows of bottles. And as the bottles drop onto the cushion they are gravitational- 30 ly fed to the opposite sides of the refrigerator and from thence by inclined runway to a central bottle dispensing position.

It will further be noted that from the introduction of a bottle at the top of the refrigerator as 35 described, and until it is discharged at the bottom opening controlled by door 44, they are all under gravity control and are all fed by cushioned inclined angular baffles and cushioned directing runways until the bottle is received at the discharge 40 point, unbroken.

Having thus described our invention what we claim is:

1. In a dispensing device comprising a housing having a bottle receiver therein, said housing having a top opening, spaced metal strips forming a vertically disposed passage between said receiver and said opening, bottle guides disposed within said passage and including horizontally disposed staggered metal members which have 45 ends attached to said strips, the opposite ends of said members being projected into the passageway; cooperating inclined metal members having their top ends attached to said strips above the respective horizontal members, said inclined members having their opposite ends resting on the second mentioned ends of the horizontal members; clips carried by said strips above said top ends; and rubber cushions held by said strips and freely suspended on said inclined members, so 50 that a bottle inserted in said opening may successively engage said cushions and move gravitationally downwardly in a curved path to said receiver, said cushions being adapted to cause the bottle to rotate in opposite directions during its descent whereby to retard its travel.

2. A bottle dispensing device of the class described comprising opposed spaced metal strips having a vertical passage therebetween; staggered brackets carried by said strips, each of said 55 brackets comprising a horizontally disposed rigid sheet member which has one end fixed to adjoining strips, said member being projected limitedly into the passage and having its other end turned downwardly, an inclined top sheet member having its top end fixed to

the adjoining strips, said top member having its lower end embracing said downwardly turned end; a clip carried by the last mentioned strips above said inclined member, a rubber sheet having its top end held by said clip, the body of said sheet and its lower end being freely disposed on said inclined member in covering relation therewith; whereby a descending bottle may successively engage said rubber sheets and travel in a practically curved path, the free portions of 10 said sheets being adapted to stretch or yield when the bottle first engages them, said free portions being then adapted to contact or move backwardly, whereby to rotate the bottle and retard the travel thereof. 15

3. In combination, means forming an upright passage chamber for bottles and the like, said chamber having its opposite sides respectively formed with staggered series of guide projections having upper soft highly frictional cushioned 20 frictional guide faces respectively; each guide face engaging a bottle rolling down said face, to give it a spinning movement to project it to the opposite side of the chamber with the advance face of the bottle moving downwardly relative 25 to its following face, and adapted while thus moving, to engage the next lower guide face on the opposite side of the chamber; the downward movement of said advance face, when it engages 30 said next lower face tending to raise the bottle to retard its fall, said next lower face then frictionally firmly engaging and rotating the bottle in the opposite direction and again projecting it; the frictional quality of the face giving to the face enough frictional hold on the bottle, to give high speed rotation to the bottle as it leaves one face; said high speed rotation and the frictional hold of said next lower face being sufficient to cause a pause in the bottle when received, thereby to temporarily nullify and therefore retard the downward movement of the bottle, 35 whereby breakage is prevented no matter how far a bottle may fall upon another in said space. 40

4. In combination, means forming an upright passage chamber for bottles and the like, said 45 chamber having its opposite sides respectively formed with staggered series of guide projections having upper concaved highly frictional cushioned faces respectively; said guide face engaging a bottle rolling down said face, to give it a spinning movement to project it to the opposite side of the chamber with the advance face of the bottle moving downwardly, the downward movement of said advance face, when it engages the 50 next lower guide face tending to raise the bottle to retard the fall of the bottle, said next lower face then frictionally and centripetally firmly engaging and rotating the bottle in the opposite direction and again projecting it; the concavity of said frictional upper guide face exerting centripetal force upon said bottle, thereby increasing the friction upon the bottle to facilitate rotating the bottle; said centripetal force and the frictional quality of the face giving to the face 55 enough frictional hold on the bottle, to give high speed rotation to the bottle as it leaves one face; said high speed rotation and the centripetal force and the frictional hold of the next lower face being substantially sufficient to cause a rise in 60 the bottle when received, thereby to temporarily nullify and therefore retard the downward movement and acceleration of the bottle to low maximum, whereby breakage is prevented when the bottles strike one upon the other 65 70 75

no matter how far the bottles may travel in the chamber.

5. In combination, means forming an upright passage chamber for bottles and the like, said chamber having its opposite sides respectively formed with staggered series of guide projections having upper concaved faces respectively; a soft highly frictional cushion covering each upper face to form an upper frictional concaved guide face; 10 each guide gradually curving from a steep angle at its upper part to a less steep angle at its lower part, approximating an obtuse angle with the upright axis of the chamber; said guide face engaging a bottle rolling down said face, to give to the 15 bottle a spinning movement to project it to the opposite side of the chamber with the advance face of the bottle moving downwardly relative to its following face, the bottle being adapted while thus moving, to engage the next lower guide face 20 on the opposite side of the chamber; the down-

ward movement of said advance face, when it engages said next lower face tending to raise the bottle on said face, thereby to retard the fall of the bottle, said next lower face, then frictionally and centripetally firmly engaging and rotating the bottle in the opposite direction and again projecting it; the concavity of said frictional upper guide face exerting centripetal force upon said bottle, thereby increasing the friction upon the bottle to give high speed rotation to the bottle as 10 it leaves one face; said high speed rotation and the centripetal force and the frictional hold of the next lower face being sufficient to cause a pause in the bottle when received, thereby to temporarily reduce to low maxima the speed and 15 acceleration of the bottle to prevent breakage no matter how far the bottles may fall one upon another. 5
